UNITED STATES PATENT OFFICE.

KIRBY S. REIST, OF SAN FRANCISCO, CALIFORNIA, ASSIGNOR TO MERGENTHALER LINOTYPE COMPANY, A CORPORATION OF NEW YORK.

TYPOGRAPHICAL MACHINE.

1,119,538.

Specification of Letters Patent.

Patented Dec. 1, 1914.

Application filed September 10, 1914. Serial No. 860,978.

To all whom it may concern:

Be it known that I, KIRBY S. REIST, a citizen of the United States, residing at San Francisco, in the county of San Francisco and State of California, have invented certain new and useful Improvements in Typographical Machines, of which the following is a specification, reference being had thereto in the accompanying drawing.

10 My invention relates to typographical machines, such as linotype machines of the general organization represented in Letters Patent of the United States, No. 436,532, to O. Mergenthaler, wherein circulating matrices are released from a magazine or magazines in the order in which their characters are to appear in print and then assembled in line, the composed line transferred to the face of the mold, the mold filled with molten 15 metal to form a slug or linotype against the matrices which produce the type characters thereon, and the matrices thereafter returned through distributing mechanism to the magazine from which they started.

20 More particularly, it relates to the escapement means for controlling the release of the matrices from the magazines.

In the accompanying drawing, I have shown my invention in preferred form and 25 by way of example, and as applied to the specific style of machine mentioned. However, many changes and variations may be made therein, and in its mode of application, which will still be comprised within its 30 spirit. Similarly, it may be applied to other forms of typographical machines, such as typesetters, typecasters and the like, which handle type or dies, instead of matrices. Generally speaking, I desire it to be 35 understood that I do not limit myself to any specific form or embodiment, except in so far as such limitations are specified in the 40 claims.

45 Referring to the drawing: Figure 1 is a sectional view through the lower portion of the magazines, etc., with my improvements embodied therein; Figs. 2, 3 and 4 are detached views illustrating the operation of the escapement in successive stages; Fig. 5 50 is a sectional view on the line 5—5 of Fig. 2; and Figs. 6 and 7 are detached perspective views of the escapement and matrix respectively.

The matrices X are stored in the usual 55 manner in the channeled magazines A, A¹,

any one of which may be brought into operative relation to the assembling devices, as represented in the present instance by the throat or raceway C, the delivery of the matrices from the selected magazine to the raceway being controlled by the longitudinally movable escapements B. In the illustrated form, a single series of escapements is employed, these being slidably mounted upon or in proximity to the raceway, in such manner that they will coöperate with the matrices of the operative magazine, all in the manner well understood in the art.

Each escapement B is in the form of a flat plate located (see Fig. 5) in a plane at the side of and parallel to the plane of the matrices in the corresponding channel, and provided with a lateral projection or lip D, which engages beneath the lowermost matrix in the channel and in normal position 70 retains the entire column therein (see Fig. 1). Each matrix X is formed in its side face with a longitudinal groove X¹, extending from its bottom diagonally across its face and opening outward at its top, that is 75 to say, so as to permit the passage of the lip D therethrough. The necessary edgewise movement of the plate B from its normal position of engagement with the matrix to the point where it registers with the groove 80 X¹ may be effected in any desired manner, such for instance as by the elbow lever B¹ and reed B², the specific form of these actuating means constituting no part of my 85 present invention.

The various positions assumed by the escapement B with reference to the matrix X are illustrated in Figs. 1 to 4: Fig. 1 shows the normal position of the parts with the lip D out of registry with the groove X¹ and sustaining the matrix; in Fig. 2 the plate B has been moved edgewise to register the lip with the groove; in Fig. 3 the matrix has begun its descent and the lip has partially traversed the groove; and in Fig. 4 the lip is at the upper end of the groove and the matrix is about to drop. As best shown in Figs. 3 and 4, it will be observed that as the lip passes along the inclined groove, the plate B returns toward its original or normal position, when the lip engages beneath the next matrix in series and retains it until the escapement is again actuated. This return movement of the plate is or may be effected partly by gravity and partly by the 90 95 100 105 110

engagement of the inclined groove with the lip as the matrix passes downwardly. If desired, springs or other suitable means may be also connected to the plate to insure and expedite its return to normal position.

As previously stated, I have shown my invention only in preferred form and by way of example, and in a specific mode of adaptation. However, many modifications and 10 alterations both in its form and application, will suggest themselves to those skilled in the art, without departure from its scope.

Having thus described my invention, its construction and mode of operation, what I 15 claim and desire to secure by Letters Patent of the United States, is as follows:

1. In a typographical machine, the combination of a magazine containing a column of type or matrices, each formed in its side 20 face with a longitudinal groove, and an escapement comprising a plate formed with a laterally projecting lip to engage the type or matrices, the said plate being movable edge-wise of the type or matrices to register its lip with the grooves in said type or matrices and thus permit their escape.

2. In a typographical machine, the combination of a magazine containing a column of type or matrices, each formed in its side 30 face with a longitudinal groove extending throughout its body portion, and an escapement comprising a plate formed with a laterally projecting lip to engage the bottom edge of the lowermost type or matrix in the column, said plate being movable to register

its lip with the groove in said lowermost type or matrix so as to permit its escape from the magazine.

3. In a typographical machine, the combination of a magazine containing a column of 40 type or matrices each formed in its side face with a longitudinal groove extending throughout its body portion, and an escapement comprising a plate formed with a laterally projecting lip to engage the bottom 45 edge of the lowermost type or matrix in the column, said plate being movable to register its lip with the groove in said lowermost type or matrix so as to permit its escape from the magazine, and the grooves in said 50 type or matrices being arranged diagonally across their faces to permit the plate to return to its original position.

4. In a typographical machine, the combination of a magazine containing a column of 55 type or matrices, each formed in its side face with a longitudinal groove extending diagonally across its face, and an escapement comprising a movable plate to control the release of the type or matrices from the 60 magazine, one at a time, and formed with a laterally projecting lip to engage in said grooves.

In testimony whereof, I have affixed my signature in presence of two witnesses.

KIRBY S. REIST.
